UNITED STATES PATENT OFFICE.

CARL L. DORER, OF BELLAIRE, OHIO.

APPARATUS FOR FIRE FINISHING AND POLISHING GLASSWARE.

No. 834,275.

Specification of Letters Patent.

Patented Oct. 30, 1906.

Application filed April 27, 1906. Serial No. 813,959.

To all whom it may concern:

Be it known that I, CARL L. DORER, a citizen of the United States of America, and a resident of Bellaire, county of Belmont, and State of Ohio, have invented certain new and useful Improvements in Apparatus for Fire Finishing and Polishing Glassware, of which the following is a specification.

My invention relates to new and useful improvements in apparatus for fire polishing and finishing glassware; and it consists in the particular construction, arrangement, and combination of parts, which will hereinafter be fully described.

15 The object of the invention is to provide a simple and efficient machine whereby articles of glassware are automatically fire finished and polished at one operation.

A further object is to provide a machine 20 the capacity of which for finishing and polishing articles of glassware is not only very much in excess of that of prevailing devices, but which possesses many advantages over said prevailing devices, some of which 25 will hereinafter be made apparent; and a still further object is to provide a conveyer by means of which the articles of glassware are transported from a point convenient to the presses to a point near the annealing-leers.

30 With the rotating type of finishing-machines which is in more or less common use the centrifugal action of the machine tends to flare the heated articles which are carried thereby on the outer sides, thus giving the 35 articles a lop-sided appearance. This objection is obviated in the present device, since the articles are thereby carried in a straight line.

40 In describing the invention in detail reference is herein had to the accompanying drawings, forming a part of this specification, in which—

Figure 1 is a side elevation of the invention. Fig. 2 is a partial longitudinal sectional view of the same. Fig. 3 is a cross-section on the line 3 3, Fig. 1; and Fig. 4 is a rear end elevation of the invention.

45 Referring to said drawings, in which like reference-numerals designate like parts throughout the several views, 1 1 indicate two parallel longitudinal girders which are mounted upon suitable supports 2, said girders forming the framework upon which rests the operating mechanism of the machine. Mounted in suitable bearings 3 and 50 4 at opposite ends of the frame are trans-

verse shafts 5, each of which carries a centrally-located sprocket-wheel 6 fast thereon, said sprocket-wheels being connected by an endless sprocket-chain 7. The bearings 3 50 at one end of the machine are so attached to the girders 1 as to be longitudinally adjustable, the purpose being to provide means whereby the tension of the chain may be adjusted. While various means may be employed for this purpose, I prefer to employ longitudinally-movable extension-arms 3^a, between the shoulders 3^b of which and the end of the girder 1 a suitable wedge 3^c may be driven. Carried by said chains 7 is a 70 plurality of holders 8, on which the articles of glassware are carried. This holder carries a receiver 9, which may be of any size or shape requisite for holding the article of glassware to be finished, a cup-shaped receiver being shown in the present instance for receiving or holding tumblers and the like. Said holder 8 consists of a broad base-plate 10, which is rigidly secured to a link of the chain 7 in a suitable manner, a box-plate 11, carried by said base-plate, a revolute spindle 12, vertically mounted at its lower end in said base-plate and projecting through the horizontal portion of said box-plate, and said receiver 9, the latter having 75 a boss 13 on its under side in which the upper end of the spindle 12 is rigidly held. Rigidly mounted on said spindle 12, between the base-plate 10 and the horizontal portion of the box-plate 11, is a small cog wheel or 80 pinion 14, which is adapted to engage a toothed rack 15, provided at a suitable point, as will hereinafter be explained, for rotating said spindle and the receiver which 85 is carried thereby.

90 A track is formed by two oppositely-disposed angle-bars 16, over which the forward traveling portion of the machine travels, the chain 7 being carried between the adjacent edges of the two angle-bars, while the under faces of the base-plates 10 on opposite sides of the chain slide upon the horizontal portions of said angle-bars, this construction 95 providing for the smooth and regular travel of the holders 8, bearing the articles of glassware. A second or return track is formed for carrying the returning portion of the chain 7, said track comprising two oppositely-disposed angle-bars 17, on the horizontal portions of which slide the then under faces of the upturned base-plates 10 on opposite sides of the pinion 14, while the por-

tion of the holders 8 carried by said base-
plates depend therefrom and travel between
the adjacent edges of the two angle-bars 17.
The ends of each of said angle-bars 16 and 17
5 are split, and the vertical sides thereof are
turned or flared outward and the horizontal
sides thereof are turned downward, thus pro-
viding guides for properly directing the base-
plates as they enter upon and leave the said
10 tracks.

The angle-bars 16 are supported upon two
or more cylindrical bodies 18, which are ec-
centrically mounted on shafts 19, having
15 their ends journaled in the opposite girders 1,
as shown. The vertical sides of said angle-
bars abut against annular shoulders or
flanges 20, provided at the ends of said cylin-
drical bodies 18, and, as is apparent, by turn-
ing the shaft 19 the height at which the hold-
ers travel in passing forward through said
20 machine may be readily adjusted. Adjust-
ing-nuts 21 are provided on said shafts 19, by
means of which the latter may be secured in
any desired position.

25 As driving mechanism for said machine a
small motor 22 is mounted upon a suitable
support, as 23, which stands upon the frame,
the pinion 24 on the motor-shaft 25 meshing
with a gear-wheel 26, provided upon the end
30 of a shaft 27, which has a perpetual screw or
worm 28 thereon, which acts upon the teeth
of a wheel 29, fast upon a suitably-mounted
transverse shaft 30, communicating a rotary
motion thereto. A sprocket-wheel 31 is also
35 mounted on said shaft 30, said wheel being
connected by a sprocket-chain 32 with a
sprocket-wheel 33, which is mounted on a
transverse shaft 34, journaled in the opposite
girders 1 of the frame. Mounted in a suit-
40 able position on said shaft 34 is a second
sprocket-wheel 35, which is connected by a
sprocket-chain 36 with a sprocket-wheel 37,
provided on the shaft 5 at the rear end of the
frame.

45 While I have described more or less par-
ticularly a gearing suitable for driving the
machine, it will be understood that this is
but one of a variety of methods or ways in
which the machine may be geared. Therefore
50 it will be noted that I do not wish to limit
myself to the gearing mechanism herein de-
scribed, it being merely employed herein in
order to show an operative mechanism.

Located on the frame at a suitable point,
55 preferably near the front end thereof, is a
furnace 38, consisting in part of side walls 39
of brick, fire-clay, or other suitable material,
mounted upon laterally - adjustable angle-
plates 40, located at each side of the path of
60 travel of the chain 7 and ware-holders 8, and
of a cover or dome 41, mounted on said side
walls 39. Said side walls 39 are each formed
with a horizontal or substantially horizontal
ledge 42 on their inner faces, and entering the
65 furnace through the dome 41 directly over

the horizontal ledges 42 are gas-pipes 43,
each adapted for directing a flame against
the ledge 42. Said gas-pipes 43 lead from a
large gas-pipe 44, which serves as a reservoir
70 for containing a reserve gas-pressure, where-
by a steady flow of gas to said pipes 43 is pro-
vided for. At a point above the dome 41
said gas-pipes enter air-blast pipes 45, which
are connected with a large air-conductor 46.
Said air-pipes entering the furnace together
75 with the gas-pipes direct the flames from the
burning gas in the form of a blast against the
faces of the ledges 42, from which said flame
is horizontally deflected over the tops of the
articles of glassware which are being carried
80 through the furnace, reheating said articles
without the flames coming into actual con-
tact therewith. Thus the rough and uneven
edges carried by the ware after leaving the
molds or presses are melted down, so that the
85 ware after passing through said furnace pre-
sents a perfectly-true smooth edge. This
reheating further imparts to the ware a rare
luster and brilliancy.

Attached to the vertical portion of one of
the angle-bars 16 and extending from one
90 end of the furnace 38 to the other is the
toothed rack 15, which is adapted to be en-
gaged by the pinion 14 of the holders 8 to ro-
tate the spindles and the articles of ware car-
ried thereby as they pass through the fur-
nace, the rotation of the ware providing for
95 the even heating thereof as it passes through
the furnace.

Connected to the large angle-plates 40, on
100 which the furnace-walls are mounted, are
lugs 47, which are slidable upon lateral arms
48, secured to the outer faces of the girders 1.
A bolt 49, carried by each lug 47, is slidable
in a slot 50, provided in the arm 48. The
105 walls of the furnace may be adjusted rela-
tively to each other to adapt it for the pas-
sage therethrough of articles of glassware of
different sizes by the manipulation of the
parts just described.

110 The general operation of the apparatus is
as follows: The articles of ware immediately
after being formed in the presses are placed
one at a time upon the holders 8 at the front
end of the machine. Said holders are being
115 carried by the traveling chain 7 at a regular
and uniform rate of speed. Hence while still
hot from the press the said articles are carried
into and through the furnace, being therein
subjected to the intense heat of the fire-
120 blasts which are deflected by the ledges 42
over the tops of the articles of ware without
actually coming into contact therewith. The
rough edges of the ware are fused, forming a
perfectly smooth and even surface or edge
125 upon the articles, and at the same time the
ware is polished from contact with said heat.
In passing through the furnace the holders
bearing the ware are rotated, thus rotating
the ware, so that all sides thereof are sub-
130

jected to the same degree of heat. Having passed through the furnace, the ware is conveyed to the opposite end of the machine, which is preferably located at a point convenient to the annealing-leers, where the articles are one by one removed from the holders.

It will be noted that the interval or space between adjacent holders 8 is small, and since the chain carrying said holders travels constantly at a uniform rapid rate of speed the capacity of the machine or apparatus is very great.

Various changes or alterations may be resorted to without departing from the general spirit or scope of the invention. Hence I do not desire to limit myself to the precise construction and arrangement of parts herein shown and described.

What I claim as new, and desire to secure by Letters Patent, is—

1. In apparatus for fire finishing and polishing glassware, a longitudinal frame, a furnace with relatively adjustable side walls mounted on said frame, horizontal ledges formed on said side walls, a conveyer traveling through said furnace, and ware-holders mounted on said conveyer and means for directing a heat blast directly against said ledges, the latter being adapted for deflecting the flames of the blast across the furnace above the ware carried by said holders.

2. In apparatus for fire finishing and polishing glassware, a longitudinal frame, a furnace with relatively adjustable side walls mounted on said frame, horizontal ledges carried on the inner sides of said side walls, a conveyer-chain for traveling through said furnace, rotatable ware-holders carried by said chain and gas-burners located over said ledges for directing heat blasts directly against the ledges, substantially as described.

3. In apparatus for fire finishing and polishing glassware, a longitudinal frame, a furnace with relatively adjustable side walls having a longitudinal passage-way therethrough located upon said frame, cylindrical bodies eccentrically mounted in said frame, a track mounted on said bodies, an endless conveyer carried by said frame, and traveling on said track, ware-holders mounted on said conveyer, and means whereby said holders are rotated while traveling through said passage-way.

4. In apparatus for fire finishing and polishing glassware, a longitudinal frame, a furnace located over said frame, the walls of said furnace being adjustable with relation to each other, said furnace having a longitudinal passage-way therethrough, an endless traveling conveyer carried by said frame, ware-holders mounted on said conveyer, means for rotating said holders as they pass through said passage-way, and means for relatively adjusting said conveyer and furnace said means comprising eccentrically-

mounted bodies and a track for said conveyer mounted upon said bodies.

5. In apparatus for fire finishing and polishing glassware, a furnace having a longitudinal passage-way therethrough, relatively adjustable side walls to said furnace, an endless conveyer-chain traveling through said passage-way, driving means and gearing for said chain, rotary ware-holders mounted on said chain, means for rotating said holders as they travel through said passage-way, horizontal ledges formed on the inner faces of said side walls, and means whereby the ware is subjected to a downwardly-directed heating blast without coming into contact with flame while passing through said furnace.

6. In apparatus of the character described, a longitudinal frame, an endless-chain conveyer suitably mounted on said frame, a plurality of ware-holders mounted on said conveyer, a track on which said ware-holders travel, a furnace having a longitudinal passage-way therethrough located over said frame, means whereby a forced downwardly-directed heat blast is secured in said furnace, and means for deflecting the flame over the tops of the articles of ware carried by said holders said means being adapted to prevent said flame from coming into actual contact with the ware.

7. In apparatus of the character described, a frame, an endless traveling chain conveyer mounted on said frame, ware-holders carried by said conveyer, a track over which said ware-holders travel and by means of which they are held upright and caused to travel smoothly, a furnace having a longitudinal passage-way therethrough located over said conveyer, means for producing a downwardly-directed heat blast in said furnace, and means for preventing the flames from contacting with the ware carried through the furnace the last-mentioned means comprising a ledge on the inner face of each side wall of the furnace adapted to deflect said flames across the passage-way above the ware.

8. In apparatus of the character described, a furnace having a longitudinal passage-way therethrough, the walls of said furnace being relatively adjustable for regulating the width of said passage-way, a ledge on the inner face of each side wall, a traveling conveyer passing through said passage-way, gas-burners located over said ledges, and means whereby a forced heat blast is directed downwardly against each of said ledges, said ledges being adapted to deflect the flame across the passage-way above the tops of the articles of glassware carried by said conveyer.

9. In apparatus of the character described, a furnace having a longitudinal passage-way therethrough, the walls of said furnace being relatively adjustable for regulating the width of said passage-way, horizontal ledges formed on the inner faces of said walls for re-

ceiving the flames of a forced vertical blast and for deflecting said flames across said passage-way, a longitudinal conveyer for carrying articles of glassware through said passage-way, means for adjusting the height of said conveyer with respect to said furnace, and gearing for driving said conveyer.

10. In apparatus of the character described, a furnace having a longitudinal passage-way therethrough, the side walls of said furnace being relatively adjustable for regulating the width of said passage-way, horizontal ledges formed on the inner faces of said side walls for receiving the flames of a forced downwardly-directed blast and for deflecting said flames across said passage-way, a longitudinal frame, an endless-chain conveyer carried by said frame, ware-holders mounted on said conveyer, and means for driving said conveyer.

11. In apparatus of the character described, a furnace having a longitudinal passage-way therethrough, the side walls of said furnace being relatively adjustable for regulating the width of the passage-way, horizontal ledges formed on the inner faces of said side walls for receiving the flames of a forced downwardly-directed blast and for deflecting said flames across said passage-way, a longitudinal frame, an endless-chain conveyer carried by said frame, ware-holders mounted on said conveyer, coacting means carried by said holders and by said furnace whereby said holders are rotated as they pass through said furnace, and means for driving said conveyer.

12. In apparatus of the character described, a furnace having a longitudinal passage-way therethrough, the side walls of said furnace being relatively adjustable for regulating the width of the passage-way, horizontal ledges formed on the inner faces of said side walls for receiving the flames of a forced downwardly-directed blast and for deflecting said flames across said passage-way, a longitudinal frame, an endless-chain conveyer carried by said frame, ware-holders mounted on said conveyer, coacting means carried by said holders and by the frame within said passage-way whereby said holders are rotated as they travel along said passage-way, a motor, and gearing connected with said motor for driving said conveyer.

13. In apparatus of the character described, a furnace having a longitudinal passage-way therethrough, the side walls of said furnace being relatively adjustable for regulating the width of the passage-way, horizontal ledges on the inner faces of said side walls, a longitudinal frame, an endless-chain conveyer carried by said frame, ware-holders mounted on said conveyer, said ware-holders each comprising a base-plate attached to a link of said chain, a box-plate carried by said base-plate, a vertical spindle journaled in

said plates, a ware-receiver mounted upon the upper end of said spindle, and a pinion on said spindle; a toothed rack adapted to be engaged by the pinions as the ware-holders pass through the furnace, a track on which said holders slide, and driving mechanism for said conveyer-chain.

14. In apparatus of the character described, a frame, an endless traveling chain conveyer carried by said frame, shafts carried by said frame, cylindrical flanged bodies eccentrically mounted on said shafts, angle-bars mounted upon said cylindrical bodies, said angle-bars constituting a track, a furnace having a longitudinal passage-way therethrough located over said frame, ware-holders mounted on said chain, said ware-holders being adapted for traveling along said track, and means for driving said chain.

15. In apparatus of the character described, a frame on which is suitably mounted a conveyer mechanism, a furnace having a passage-way therethrough located over said conveyer mechanism, said furnace comprising adjustable side walls having ledges formed thereon, and a dome, gas-pipes entering said furnace through the dome thereof, said gas-pipes entering within air-blast pipes whereby a forced flame is directed against said ledges and is deflected by said ledges across said passage-way, and driving mechanism for said conveyer mechanism.

16. In apparatus of the character described, a longitudinal frame, shafts journaled in said frame at each end thereof, a sprocket-wheel carried by each shaft, an endless sprocket-chain connecting said sprocket-wheels, driving mechanism and gearing for said chain, means for adjusting said chain, ware-holders mounted on said chain, cylindrical bodies eccentrically mounted in said frame, a track for guiding said holders mounted on said bodies, the latter being adapted for employment for adjusting the elevation of said track, and a furnace suitably located for fusing the edges of articles of glassware carried by said holders, said furnace being adapted for directing flames over the ware carried by the ware-holders without said flames contacting with said ware.

17. In apparatus of the character described, a longitudinal frame, shafts journaled in said frame at each end thereof, a sprocket-wheel carried by each shaft, an endless sprocket-chain connecting said sprocket-wheels, driving mechanism and gearing for said chain, ware-holders mounted on said chain, a track on which the bases of said holders are carried at each side of said chain, eccentrically-mounted means for adjusting the elevation of said track, a furnace located over said frame, said furnace having adjustable side walls, horizontal ledges on the inner faces of said side walls for receiving the flames of a forced downwardly-directed blast

and for directing said flames over the top of the ware carried by said ware-holders without said flames contacting said ware.

18. In apparatus of the character described, a longitudinal frame, shafts journaled in said frame at opposite ends thereof, sprocket-wheels carried by said shafts, an endless chain connecting said sprocket-wheels, driving mechanism and gearing for said chain, ware-holders mounted on said chain, a track on which the bases of said holders are carried at each side of said chain, means for adjusting the elevation of said track, a furnace located over said frame, the side walls of said furnace carrying horizontal ledges on their inner faces and being relatively adjustable, and gas-feed pipes entering said furnace and connected with air-blast pipes whereby the ignited gas is directed against said ledges and is caused to be deflected therefrom over the articles of ware carried by said ware-holders.

19. In an apparatus of the character described, the combination with a frame and a conveyer-chain, of a plurality of ware-holders mounted on said chain, each holder comprising a base-plate secured to a link of said

chain, a box-plate carried by said base-plate, a vertical spindle rotatably mounted in said plates, a ware-receiver carried by the upper end of said spindle, and a pinion on said spindle between said base-plate and said box-plate.

20. In an apparatus of the character described, the combination with a frame and a conveyer-chain, of a plurality of ware-holders mounted on said chain, each holder comprising a base-plate secured to a link of said chain and projecting laterally beyond said chain, a box-plate carried by said base-plate, a vertical spindle rotatably mounted in said plates, a ware-receiver carried by the upper end of said spindle, and a pinion on said spindle; a rack adapted to be engaged by the pinions to rotate said ware-holders, and a track on which slide the base-plates of said holders at opposite sides of said chain.

In testimony whereof I affix my signature in presence of two subscribing witnesses.

CARL L. DORER.
